UNITED STATES PATENT OFFICE.

HARRY G. POTTLE, OF CHICAGO, ILLINOIS, ASSIGNOR, BY MESNE ASSIGNMENTS, TO THE LUDLOW TYPOGRAPH COMPANY, OF CHICAGO, ILLINOIS, A CORPORATION OF ILLINOIS.

TYPOGRAPH MECHANISM.

1,414,707.

Specification of Letters Patent. Patented May 2, 1922.

Application filed August 23, 1919. Serial No. 319,397.

To all whom it may concern:

Be it known that I, HARRY G. POTTLE, a citizen of the United States, and a resident of Chicago, county of Cook, and State 5 of Illinois, have invented a new and useful Improvement in Typograph Mechanism, of which the following is a specification, the principle of the invention being herein explained and the best mode in which I have 10 contemplated applying that principle, so as to distinguish it from other inventions.

The present improvements, relating, as indicated, to typograph mechanism, have more particular regard to holders for matrix bars such as are employed in the so-called Ludlow typograph (see U. S. Letters Patent No. 1,266,156 to William A. Reade, dated May 14, 1918). In such typograph the holder is an independent member 15 arranged to receive and hold a number of detached matrix bars in selected relation, thereby forming a composite matrix apart from, but adapted to co-operate with, a mold when said holder is temporarily secured to a suitable support. The detached 20 matrix bars, or "matrices" as they are ordinarily called, are in effect plates or blocks of uniform length and height, but of varying width, to accommodate character im- 25 pressions of correspondingly varying width. The character impressions are struck or driven in the bottom of recesses cut in what may be called the lower edges of the bars, and it is the practice, for reasons that need 30 not be explained, to center such characters on a transverse median line. Accordingly, an assemblage of matrices selected from the same font will have the lower edges of the character impressions properly aligned, but 35 when it is desired to set up matter in which some of the letters or other characters are displaced above or below the normal line, a special matrix obviously requires to be provided.

40 The object of the present invention is to provide a holder of the character described, wherein the matrices may be individually displaced transversely of such holder so as to locate the character impression either 45 above or below the normal alignment, as may be desired.

To the accomplishment of the foregoing and related ends, the invention, then, con-

sists of the means hereinafter fully described and particularly pointed out in the 55 claims, the annexed drawing and the following description setting forth in detail certain mechanism embodying the invention, such disclosed means constituting, however, but one of various mechanical forms 60 in which the principle of the invention may be used.

In said annexed drawing:—

Fig. 1 is a top plan view of a holder such as is employed in the Ludlow typograph, a portion of one side thereof being broken away to show the interior construction; Fig. 2 is a bottom plan view of such holder, showing a series of matrix bars held therein; Figs. 3 and 4 are transverse sections of such 70 holder and matrix bars, the planes of the sections being respectively indicated by the lines 3—3 and 4—4, Fig. 2; and Fig. 5 illustrates an impression or print made from a composite matrix assembled in the present 75 improved holder.

The holder, in the commercial structural form illustrated, comprises two end pieces 1 and 2 secured to side members 3 and 4 of sufficient length to provide an opening 80 somewhat larger than the maximum length of the slug which it is desired to cast. Slidably mounted between said side members, at one end of the holder, is a clamp member in the form of a block 5 that is engaged 85 by the threaded portion of a screw 6 rotatably secured in the adjacent end piece 2, and provided with a knurled head. Obviously by rotating such screw the block 5 can be advanced or retracted to clamp, or 90 release as desired, the assembled matrix bars 7, as shown in Fig. 2.

The latter are of the general form illustrated in Figs. 3 and 4, the character impressions 8 being struck or driven in the bottom of recesses 9 cut in the lower edges of said bars. The upper portions of the matrix bars project laterally in the form of ears 10 that are adapted to rest on the side pieces 3 and 4 of the holder, leaving the bodies of the bars depend between and some distance below such side pieces. In order to facilitate the insertion of the matrix bars in the holder, the inner face of at least one thereof 100 is slightly beveled or flared upwardly, a 105 close fit being secured, however, between

- their lower edges and the bars so as to insure the correct alignment of the latter in a horizontal plane. The extent of the assembled line of bars or matrices can be 5 readily determined by graduations 11 on the upper face of the side piece 4, and if necessary the line may be filled out, as well as proper spaces provided, by the insertion of blank bars, as will be readily understood.
- 10 When a line of proper length has been assembled, the bars are clamped longitudinally of the holder by turning the screw 6, and the holder may then be placed in the typograph machine and a slug cast, taking the 15 impression of the assembled character impressions on the under faces of the bars, as need not be further explained.

In the present improved holder, instead of both side pieces 3 and 4 having solid inner faces, the one such piece 3 is provided with a series of spring-pressed plungers 12, as best shown in Figs. 1, 3 and 4, the inner ends of which normally project an equal distance within the opening between the side 20 members so as to leave just the proper space for the insertion of the matrix bars 7, further movement being prevented by heads 13 on such plunger. The plungers, as well as the springs 14, which thus normally position 25 the same, are retained in place in the side piece by means of a plate 15 that closes the openings in which such plungers and springs are received.

When now it is desired to displace any 30 particular character impression, with respect to the normal line, by inserting a plate or liner 16 of proper thickness, and of a length corresponding to the width of the matrix bar or bars to be displaced, the latter may obviously be shoved over into contact with the flat inner face of side piece 3, or to any position short of such contact, within the limit of movement of the plungers 12. The effect of such displacement is 40 shown in Fig. 5, illustrating the word "THE" set up with the second and third letters aligned with an upper edge of the first letter. The utility of the present holder in setting up price marks, applying letters 45 or numerals as suffixes, etc., will be readily apparent from the foregoing.

It will be understood that the plungers 12 are closely enough spaced to insure the engagement with one or more thereof by each 50 bar, however thin or narrow the edge of the latter. The contacting ends of said plungers are preferably rounded slightly, as shown, so as not to interfere with the adjustment of the bars longitudinally of the 55 opening in the holder in the normal position of said plungers.

Other modes of applying the principle of my invention may be employed instead of the one explained, change being made as regards the mechanism herein disclosed, pro-

vided the means stated by any of the following claims or the equivalent of such stated means be employed.

I therefore particularly point out and distinctly claim as my invention:—

1. In typograph mechanism, the combination with detached matrix bars each having an edge adapted to co-operate with a mold; of a member formed with an elongated opening adapted to receive a number of said bars 70 and support the same in selected relation with their mold-cooperative edges exposed, said bars being movable in said holder in the direction of such edges; and means adapted to vary the position of said bars in 75 such direction.

2. In typograph mechanism, the combination with detached matrix bars each having an edge adapted to co-operate with a mold; of a member formed with an elongated opening 80 adapted to receive a number of said bars and support the same in selected relation with their mold-cooperative edges exposed, said bars being movable in said holder in the direction of such edges; and means adapted to vary the position of said bars in 85 such direction independently of each other.

3. In typograph mechanism, the combination with detached matrix bars each having an edge adapted to co-operate with a mold; of a member formed with an elongated opening 90 adapted to receive a number of said bars and support the same in selected relation with their mold-cooperative edges exposed, said bars being movable in said holder in the direction of such edges; and means 95 adapted to vary the position of said bars in such direction independently of each other.

4. In typograph mechanism, the combination with detached matrix bars each having an edge adapted to co-operate with a mold;

of a member formed with an elongated opening adapted to receive a number of said bars 100 and support the same in selected relation with their mold-cooperative edges exposed, said bars being movable in said holder in the direction of such edges; and transversely displaceable means in said member disposed along one side of such opening whereby the position of said bars in such direction may be correspondingly varied.

4. In typograph mechanism, the combination with detached matrix bars each having an edge adapted to co-operate with a mold; of a member formed with an elongated opening 105 adapted to receive a number of said bars and support the same in selected relation with their mold-cooperative edges exposed, said bars being movable in said holder in the direction of such edges; and independently transversely displaceable elements in said 110 member disposed along one side of such opening whereby the position of individual bars in such direction may be varied as desired.

5. A holder for matrix-bars of the character described, comprising a member formed with an elongated opening adapted to receive and hold a number of such bars transversely disposed therein with their mold-cooperative edges exposed, and transversely displaceable means along one side of such opening whereby the position of said bars 120 may be correspondingly varied in the direction of a plane passing through the sides of said member.

6. A holder for matrix-bars of the character described, comprising a member formed with an elongated opening adapted to receive and hold a number of such bars transversely disposed therein with their mold-cooperative edges exposed, and independent transversely displaceable members along one side of such opening whereby the position of individual bars may be varied as desired in

5 the direction of a plane passing through the sides of said member.

7. A holder for matrix-bars of the character described, comprising a member formed with an elongated opening adapted to receive a number of such bars transversely disposed therein, and independent transversely displaceable plungers along one side of such opening whereby the transverse position of individual bars may be varied as desired.

Signed by me, this 20 day of August, 1919.

HARRY G. POTTLE.
